UNITED STATES PATENT OFFICE.

LARS O. GRONDAHL, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Application filed April 16, 1921. Serial No. 461,783.

My invention relates to railway signaling, and is particularly well adapted to signaling of the type wherein roadside signals are governed by track circuits which in turn ⁵⁵ are controlled by the passage of cars or trains along the track.

I will describe several forms of signaling apparatus embodying my invention, and will then point out the novel features there-⁶⁰ of in the claim.

In the accompanying drawings, Fig. 1 is a diagrammatic view showing one form of apparatus embodying my invention. Fig. 2 is a view showing a modification of the ar-⁶⁵ rangement of the apparatus shown in Fig. 1. Fig. 3 is a diagrammatic view similar to Fig. 1, but showing a modified form of apparatus also embodying my invention. Fig. 4 is a view showing a re-arrangement ⁷⁰ of portions of the apparatus shown in Fig. 3 and embodying my invention.

Similar reference characters refer to simi-
lar parts in each of the several views.

Referring first to Fig. 1, the reference ⁷⁵ characters F and F^a designate the track rails of a railway along which traffic normally moves in the direction indicated by the arrow. These rails are divided into a plurality of successive track sections A—B, B—C, C—D, etc., the isolation of the track sections being accomplished, as here shown, by insulated joints 2 in both of the lines of rails. Any other suitable method of isolat-⁸⁰ ing the sections may be employed, however, without departing from the spirit and scope ⁸⁵ of my invention.

Located adjacent the entrance end of each track section is a signal designated by the reference character S, with an exponent cor-⁹⁰ responding to the location. Each signal, as here shown, comprises three lamps G, Y and R, arranged when lighted to indicate "pro-⁹⁵ceed", "caution" and "stop", respectively.

Connected across the rails of each track section adjacent the exit end thereof is a suitable source of track circuit current, which, as here shown, is the secondary ¹⁰⁰ 3 of a transformer designated T with an exponent corresponding to the location. The primary 4 of each transformer T is connected with a transmission line 5, which is constantly supplied with alternating signaling current by a generator 6. Adjacent

the entrance end of each track section are four heating units H', H², H³ and H⁴, each of which is connected across the rails of the section. It will be seen, therefore, that each track section is provided with a track circuit comprising the rails of the section, a source of current at the exit end of the section, and ⁶⁰ four heating units connected in multiple across the rails at the entrance end of the section.

Associated with each heating unit is an element designated E with a suitable exponent, which element is responsive to variations in temperature by varying in electrical resistance. Each element E is so located as to receive heat from the associated heating unit H, and for this purpose the materials ⁶⁵ constituting the heating unit and the element will usually be in close proximity. Each element E is preferably made of a material having a large temperature co-efficient, that is, a material which responds to ⁷⁰ a given change of temperature by a com-⁷⁵paratively large change of electrical resist-⁸⁰ance. These elements may be, for example, Nernst filaments, copper oxides, or various other materials having similar properties. Each element E' has a positive temperature ⁸⁵ co-efficient, that is, its electrical resistance increases with increase of temperature. Each of the remaining elements E², E³ and E⁴ has a negative temperature co-efficient; ⁹⁰ that is, its electrical resistance decreases with increase of temperature. These characteristics of the several elements are indicated on the drawing by the symbols + and — adjacent the elements. In practice it ⁹⁵ may be found of advantage to place trans-¹⁰⁰formers in the circuits between the elements E and the lamps. The elements E control the signals S in the manner which I will now explain.

Referring specifically to signal S^c, Fig. 1, the stop lamp R is provided with a circuit which is supplied with energy from a sec-¹⁰⁵ondary 12 on transformer T^c, and which in-¹¹⁰cludes the positive co-efficient element E'. This circuit is from secondary 12, through wires 7, 8 and 9, stop lamp R, element E', and wire 10 to secondary 12. The parts of this circuit are so adjusted that when track section B—C is unoccupied, that is, when ¹¹⁵ element E' is heated, the resistance of the

circuit is such that lamp R is extinguished. When the track section B-C is occupied, however, the supply of current to the heating unit H' is diminished, so that element 5 E' cools and the consequent decrease in resistance in this element permits sufficient current to flow in the stop circuit to cause lamp R to become lighted.

The caution lamp Y of signal S^c is connected in multiple with the stop lamp R of the next signal in advance through wires 13 and 14, such stop lamp being controlled in the same manner as lamp R for signal S^c. It follows, therefore, that when track section 10 A-B is unoccupied, lamp Y of signal S^c will be extinguished, but that when section A-B is occupied by a car or train, the flow of current in lamp Y of signal S^c increases to such value that this lamp becomes 15 lighted. The circuit of lamp Y includes the negative co-efficient element E², which is controlled by the heating unit H² of section B-C. When section B-C is unoccupied, the resistance of element E² is so low that 20 it does not interfere with the control of lamp Y by the element E' at location B. If, however, a train enters section B-C while section A-B is occupied, the resistance of element E² increases to such value as to prevent 25 lamp Y from becoming lighted.

Lamp G for signal S^c is provided with a circuit which passes from a secondary 15 of transformer T^c, through wire 16, negative co-efficient element E³, wire 17, negative co-efficient element E⁴, wires 18, 8 and 13, and lamp G to the secondary 15 of transformer T^c. The parts of this circuit are so adjusted that when both elements E³ and E⁴ are heated, sufficient current flows in the circuit 30 to light lamp G. This condition exists, of course, only when both sections A-B and B-C are unoccupied. If either of these sections is occupied by a train, one or the other of the elements E³ or E⁴ will become 35 cooled and the resistance of such element will then be sufficient to reduce the current in the circuit of lamp G below the point of luminosity. The same result is attained, of course, when both of these sections are occupied.

As shown in the drawing, section A-B is occupied by a car or train W, so that all of the elements E associated with this section are cooled. Lamp G of signal S^b is extinguished because of the high resistance introduced 40 in the circuit of this lamp by element E³. Lamp Y of this signal is extinguished because of the high resistance of element E². Lamp R has become illuminated, however, because of the low resistance of element E', so that signal S^b indicates stop. In signal S^c, lamp G is extinguished, because of the high resistance of element E⁴ at location B, and lamp R is extinguished because of the 45 high resistance of the element E' at loca-

tion C. Lamp Y is lighted, however, because lamp R of signal S^b is lighted, and so it follows that signal S^c indicates caution. As for signal S^b, lamp R is extinguished because of the high resistance of element E' 50 at location D, and lamp Y is extinguished because of the high resistance of element E' at location C. Lamp G is lighted, however, because both of the elements E³ and E⁴ in circuit with this lamp are of low resistance, 55 and so signal S^b indicates proceed.

Referring now to Fig. 2, I have here shown a modification of the apparatus shown in Fig. 1 by virtue of which the amount of energy abstracted from the track circuit is 60 materially reduced. The four heating units which are connected with each track circuit in Fig. 1 are replaced by a single heating unit H in Fig. 2, which unit controls the resistance of a negative co-efficient element E. 65 This element in turn controls the heating units H', H², H³ and H⁴, through a circuit which passes (see location C) from secondary 12 of transformer T^c, through wire 19, heating unit H³, wire 20, heating unit H², 70 wire 21, heating unit H', element E, wire 22, heating unit H⁴, and wire 10 to the right-hand terminal of secondary 12. It will be seen, therefore, that when the track circuit is unoccupied, each of the heating 75 units is supplied with current, but that when the track circuit becomes occupied, the resistance of the heating unit circuit is materially increased, due to the influence of the negative co-efficient element E, and the units 80 H', H², H³ and H⁴ are then cooled. The heating units H' to H⁴ control temperature responsive elements E' to E⁴, inclusive, in the same manner as in Fig. 1, and the control of the signals S by the elements E is 85 exactly the same as in Fig. 1. The structure and operation of Fig. 2 will be apparent, therefore, without further discussion. It will be seen that with the arrangement of apparatus shown in Fig. 2, only a small 90 amount of controlling energy need be taken from the track circuit, and that the energy employed for actually heating the units H' to H⁴, inclusive, is taken from the transformer secondary 12. As in Fig. 1, 95 transformers may be introduced between the elements E and the lamps.

Referring now to Fig. 3, the three lamps R, Y and G of each signal are connected in multiple across the terminals of a secondary 100 34 of the adjacent transformer T. Included in the branch for the lamp R is an element E' having a positive temperature co-efficient. Included in the branch for lamp Y is an element E² having a negative temperature co-efficient and an element E⁵ having a positive temperature co-efficient. The branch for lamp G includes two elements E³ and E⁴, each having a negative temperature co-efficient. Each element E is provided with a 105

heating unit designated H with a suitable exponent. As in Figs. 1 and 2, the heat responsive elements may be used to control the current in the primary of a transformer the 5 secondary of which supplies the current to the lamps.

Each track section is provided with a track circuit comprising transformer secondary 3, and a heating unit designated H with an exponent corresponding to the location. Each heating unit H controls a negative temperature co-efficient element designated E with an exponent corresponding to the location. This element E controls certain of the heating units for the signal at the same location, and also certain of the heating units for the next signal in the rear. Considering element E^B , for example, the circuit for this element passes from secondary 34 of transformer T^B , through wire 24, heating unit H' , wire 23, unit H^2 , wire 25, unit H^3 , wire 26, element E^B , wire 27, unit H^4 at location C, wire 28, unit H^5 at location C, and wires 29 and 32 to secondary 34 of transformer T^B . It will be seen, therefore, that when track section A—B is unoccupied, heat is supplied to the elements E' , E^2 and E^3 at location B, and also to the elements E^4 and E^5 at location C.

Referring specifically to signal S^c , the circuit for stop lamp R is so adjusted that this lamp is extinguished when unit H' is heated; that is, when section B—C is unoccupied, and is lighted when unit H' is cold; that is, when section B—C is occupied. The lamp Y is controlled by element E^2 , which is governed by section B—C, and is further controlled by element E^5 , which is governed by section A—B. Assuming that section B—C is unoccupied, so that the resistance of element E^2 is low, this lamp is extinguished when element E^5 is hot, that is, when section A—B is unoccupied, but is lighted when element E^5 is cold, that is, when section A—B is occupied. If section B—C becomes occupied while section A—B is occupied, however, the consequent cooling of element E^2 will extinguish lamp Y . Lamp G is controlled by negative co-efficient elements E^3 and E^4 , the former of which responds to section B—C and the latter to section A—B. In order to light lamp G both of these elements must be hot, that is, both of these track sections must be unoccupied; the cooling of either element due to occupancy of the corresponding section serves to extinguish the lamp.

As shown in the drawing, section A—B is occupied by a car or train W . Lamp G of signal S^B is extinguished due to the cooling of element E^3 , and lamp Y is extinguished due to the cooling of element E^2 . Lamp R is lighted, however, due to the cooling of element E' , and so signal S^B indicates stop. Considering signal S^c , lamp G

is extinguished due to the cooling of element E^4 , and lamp R is extinguished because element E' is hot. Lamp Y is lighted, however, due to the cooling of element E^5 , so that signal S^c indicates caution. As for signal S^p , the proceed lamp G is illuminated because both elements E^3 and E^4 are hot. The caution lamp Y is extinguished because both elements E^2 and E^5 are hot, and the stop lamp R is extinguished because element E' is hot. Signal S^p , therefore, indicates proceed.

Referring now to Fig. 4, the system shown therein is a modification of the system of Fig. 3 in that the heating units at each signal location are controlled by two master units, one of which responds to the condition of the adjacent track section and the other to the condition of the track section next in advance. Each track section is provided as in Fig. 3 with a unit designated H with a letter exponent corresponding to the location. Considering location B, for example, the track circuit for section A—B includes a heating unit H^B , which controls a negative co-efficient heat responsive element E^B . This element E^B governs a master heating unit H^B_M at location B, and another master heating unit H^C_Q at location C. The circuit for these heating units passing from secondary 34 of transformer T^B , through wire 32, heating unit H^B_M , element E^B , wire 40, heating unit H^C_Q and wires 41 and 24 to the secondary 34 of transformer T^B . It will be seen, therefore, that when track section A—B is unoccupied, each of the master units H^B_M and H^C_Q is heated, but that each of these units becomes cool when section A—B is occupied by a car or train. As in Fig. 3, transformers may be added between the elements E and the lamps.

Referring specifically to signal S^c , the three heating units H' , H^2 and H^3 are governed by the master element E^c_M , the circuit being from secondary 34 of transformer T^c , through wire 24, unit H' , wire 39, unit H^2 , wire 38, unit H^3 , element E^c_M , wire 37, and wire 32 to secondary 34. The heating units H^4 and H^5 , on the other hand, are controlled by the master element E^c_Q , the circuit being from secondary 34 of transformer T^c , through wires 24 and 36, unit H^5 , wire 35, unit H^4 , master element E^c_Q and wire 32 to secondary 34. It will be seen, therefore, that the supply of current to the units H' to H^5 , inclusive, is responsive to the presence and absence of trains in exactly the same manner as with the apparatus shown in Fig. 3. The operation of the apparatus shown in Fig. 4 will be apparent, therefore, without further explanation.

Although I have herein shown and described only four forms of apparatus embodying my invention, it is understood that various changes and modifications may be

made therein within the scope of the appended claim without departing from the spirit and scope of my invention.

Having thus described my invention what I claim is:

In combination, two successive sections of railway track, a track circuit for the forward section including a source of current and a heating unit, a temperature-responsive element exposed to heat from said unit, two master heating units one for each section and

both controlled by said element, a master temperature-responsive element for each master unit, a group of secondary heating units for each section controlled by the master element for the section, a secondary temperature-responsive element for each secondary unit, and signals for the sections controlled by said secondary elements. 15

In testimony whereof I affix my signature.

LARS O. GRONDAHL.
